37,714.

UNITED STATES PATENT OFFICE.

LILLIAN G. BARROW, OF JACKSON, ALABAMA.

DESIGN FOR A VESSEL.

No. 37,714.

Specification for Design.

Patented Dec. 5, 1905.

Application filed October 21, 1905. Serial No. 283,856. Term of patent 3½ years.

To all whom it may concern:

Be it known that I, LILLIAN G. BARROW, a citizen of the United States of America, residing at Jackson, in the county of Clarke and State of Alabama, have invented a new, original, and ornamental Design for Vessels, of which the following is a specification.

Figure 1 is a side elevation of a vessel, showing my new design. Fig. 2 is a top plan view thereof.

I claim—
The ornamental design for a vessel, as shown.

LILLIAN G. BARROW.

Witnesses:

J. A. COATE,
R. A. SIMPKINS.
